PACK FOR SMALL ARTICLES OF MERCHANDISE

William F. Blamey, Jr., Stratford, Conn.

Application July 20, 1955, Serial No. 37,040

Term of patent 14 years

(Cl. D58—13)

Fig. 1.

Fig. 2.

Fig. 3.

Fig. 1 is a top view of the pack for small articles of merchandise showing my new design;

Fig. 2 is a section taken along the lines 2—2 of Fig. 1; and

Fig. 3 is a section taken along the line 3—3 of Fig. 2.

I claim:

The ornamental design for a pack for small articles of merchandise, as shown.
